CLAIM

The ornamental design for an illuminated hanging sign cabinet, as shown and described.

DESCRIPTION

FIG. 1 is a perspective front bottom view of the illuminated hanging sign cabinet showing my new design.

FIG. 2 is a rear elevational view, the opposite side of which is a mirror image thereof.

FIG. 3 is an end elevational view, the opposite end of which is a mirror image thereof.

FIG. 4 is a bottom plan view thereof.

FIG. 5 is a top plan view thereof.

FIG. 1**FIG. 2****FIG. 3****FIG. 4****FIG. 5**
